UNITED STATES PATENT OFFICE.

URWIN J. MAGILL, OF RYE, NEW YORK.

AREAWAY CONSTRUCTION.

Application filed January 20, 1928. Serial No. 248,042.

This invention relates to area-way construction in connection with building operations.

An object of the invention is the provision of an improved type of area-way structure which may be economically manufactured in the form of standardized units, adapted to be placed in position for connection to a main wall.

10 The walls of such area-way structures are customarily made of the same materials, in like manner, and at the same time as the main wall of which they form an integral part. It thus becomes necessary to build, 15 in the area-way excavation, two side walls and an outer wall (involving the making of four masonry corners); to install a window sill and a window frame and sash in the opening in the main wall; and to also install in the area-way proper a drain sill, an 20 area-way basin, and a grating or grill for covering the top of the area-way.

By the present invention, the work of 25 making such area-way structures is much simplified, and the cost thereof is materially reduced. The invention contemplates the casting from reinforced concrete, metal, or other suitable material, of a unit comprising a complete area-way wall, basin and window 30 sill, imbedded in which casting may be a window frame and grating bars or other suitable means for covering the top opening. Such a unit is placed in the area-way excavation in proper relation to the main wall, 35 which latter is then built around and attached to the shell of the unit, whereby the two become integral.

The invention will best be understood by reference to the accompanying drawings, 40 wherein Figure 1 is a fragmentary perspective view of a wall, installed in connection with which is a unit embodying one form of the invention; Figure 2 is a top plan view of the unit as it appears when installed; Figure 45 3 is a vertical section on the line 3-3 of Figure 2, looking in the direction indicated by the arrows; and Figure 4 is a vertical section on the line 4-4 of Figure 3, looking in the direction indicated by the 50 arrows.

Like reference characters indicate like parts throughout the drawings.

Referring to the drawings, 1 denotes a 55 vertical wall portion, which may be of curved, rectangular or other desired con-

tour. Integral with this vertical wall is a bottom wall 2, forming the area-way basin, which may slope downward to a centrally-disposed drain opening 3 (Figs. 3 and 4), connecting with which opening is a drain-pipe 4 (Fig. 2), which may be of standard form and cemented to the bottom wall. Alternatively, this bottom wall or basin 2 may slope rearwardly to a drain opening 3 (Fig. 1), formed in the rear portion of vertical wall 1. In the front portion of the unit (Fig. 4) is formed a window-sill 5, adjacent which sill is installed a window-frame 6, adapted to receive a sash of any desired type. The window-frame 6 may be formed of metal, wood, or other suitable material. If the shell of the unit be made of concrete, the window-frame may be either placed in the mould in such position that the concrete will be poured around the same, and, upon setting, retain it in place; or there may be provided in the casting a recess to receive the frame, which may be cemented in place after the casting material has set. If the shell be made of cast metal, the latter procedure is to be followed.

50 Grating or grille members, such as 8, in the form of bars of steel, wood, or other suitable material, may be either placed in the concrete moulds in such position that the concrete will be poured about the ends thereof, and, upon setting, retain the same in place; or suitable recesses may be cast in the shell to receive such ends, which may then be secured in position in any well-known manner.

Reinforcing members such as 11 (Fig. 4) may be placed within the mould in which the concrete is poured.

In order that the unit may be securely 95 anchored to the main wall, the shell may be provided with projecting ribs, such as 9 (Fig. 1), around which the concrete of the main wall will set; or with grooves, such as 100 10 (Fig. 2), within which such concrete will set.

The pre-cast structure may be manufactured in quantities at a low cost for labor, and the installation thereof may be readily and cheaply accomplished. It is therefore 105 possible to effect very considerable economies in this feature of building construction.

I have described what I believe to be the best embodiments of my invention. I do not wish, however, to be confined to the em- 110

bodiments shown, but what I desire to cover by Letters Patent is set forth in the appended claims.

I claim:

- 5 1. In the combination of a foundation wall, having an opening therein leading to an areaway, a unitary areaway structure adapted to be set into the said opening, and forming an integral part of the wall, comprising a cast shell having side walls fitting in said opening and formed to receive a window frame, and a bottom wall having its forward portion projecting into the opening and forming a window sill.
- 10 15 2. As a new article of manufacture, a unitary areaway structure, adapted to be built into and made integral with a foundation wall comprising a cast shell having side walls, a bottom wall, a grating imbedded in the top thereof, and a window

frame in one side wall, the portions of the side wall adjacent the window frame being adapted to be incorporated with and be made an integral portion of the foundation wall.

25 3. As a new article of manufacture, a unitary areaway structure adapted to be built into and made integral with a foundation wall comprising a cast shell, having a bottom and side walls, the side walls and forward portions of the bottom cooperating to receive a window, the said forward portion constituting a window sill, the said window sill and forward portions of the side walls being adapted to be built into an opening 30 35 in a foundation wall.

In testimony whereof I have affixed my signature to this specification.

URWIN J. MAGILL.
